Richard Oliver.

ATTORNEY

UNITED STATES PATENT OFFICE.

GEORGE A. PREISSER, OF DENVER, COLORADO.

AIR INTAKE.

Application filed May 31, 1922. Serial No. 564,837.

To all whom it may concern:

Be it known that I, GEORGE A. PREISSER, a citizen of the United States, residing at Denver, in the county of Denver and State of Colorado, have invented certain new and useful Improvements in Air Intakes, of which the following is a specification.

This invention has reference to certain new and useful improvements in auxiliary and feeding attachments for internal combustion engines.

The primary object of the invention is to provide an auxiliary air feeding device which will automatically supply air to the intake manifold in proportion to the fuel supplied from the carburetor.

Another object of the invention is to provide a connection between the supply valve of the carburetor and the auxiliary air device which is so constructed that the amount of air passing through the air feeding device will be automatically regulated whenever the carburetor valve is moved to vary the supply of fuel to the intake.

A still further object of the invention is to so construct the auxiliary air feeding device that the same may be positioned between the carburetor outlet and the intake manifold without modifying the construction of either of these parts.

A still further object of the invention is to provide means whereby steam may be withdrawn from a suitable source and admitted into the intake manifold when desirable.

A still further object of the invention is to provide a device of this character which is comparatively inexpensive to manufacture and is of such construction as to be capable of ready attachment to any standard form of carburetor and intake manifold without the necessity of expensive modification.

Other objects of the invention as well as the construction and arrangement of the parts thereof will be more readily understood from the following description and accompanying drawings, in which:

Figure 1 is a top plan view of the carburetor and an intake manifold having my invention attached thereto, the intake manifold being partly shown in section.

Figure 2 is a side elevation of the complete device in detached position, and

Figure 3 is a longitudinal sectional view taken through the body portion of the device

and showing the arrangement of the various parts.

In the present drawings, the numeral 1 is used to designate a carburetor of conventional form. The outlet pipe 2 of the carburetor is provided as usual with a securing flange 3 adapted to be bolted to a corresponding flange 4 formed on the end of the intake manifold 5.

My invention, which is adapted to be positioned between the flanges 3 and 4, consists of a body portion 6 which is in the form of a flat substantially rectangular casting. This body portion is adapted to be placed between the flanges 3 and 4 as stated and for this purpose is provided with the apertures 7 through which are passed the securing bolts 8 which hold the two flanges together. Suitable nuts 9 engaged upon the threaded end of these bolts are adapted to hold the two flanges tightly clamped against opposite sides of the body portion. The body portion is further provided with a central opening 10 which is of the same diameter as the inside diameters of the outlet 2 and intake manifold 5 and registers therewith to provide an uninterrupted passage from the carburetor to the engine cylinders. Above the opening 10 the body portion is provided with a cylindrical bore 11 which extends longitudinally along the upper edge of the body and is open at each end thereof. The upper portion of this bore is provided with a plurality of vertical air ports 13 through which air is drawn into the bore 11 and is subsequently admitted into the opening 10 through the ports 14 extending vertically through the body portion from the lower portion of the bore to the wall of said opening. A slide valve in the form of a plunger 15 is movable in the bore 11 between the air ports 13 and 14 to regulate the amount of air passing through these ports into the intake manifold by way of the opening 10. The outer end of this plunger valve is bent at right angles as indicated at 16 and has its free end flattened and apertured to provide an eye 17. A connecting rod 18 is extended through this eye and is threaded at one end to receive the nuts 19 which are positioned upon opposite sides of the eye 17 for a purpose which will be apparent hereafter. The end of the rod 18 opposite to the threaded end thereof is flattened and apertured to provide an eye

20 as clearly shown in Fig. 1. This eye 20 is adapted to register with a similar eye formed on the end of an arm 21 and is secured by a common fastening means to an 5 actuating rod 22. The arm 21 is attached to and controls the supply valve of the carburetor and is in turn actuated by the rod 22 which may be connected to any suitable 10 form of actuating lever used for this purpose. By connecting the rod 18 to the arm 21 and the rod 22 at the point of connection therebetween it will be seen that whenever movement is imparted to the carburetor 15 valve through the medium of the arm 21, a corresponding movement will be imparted to the plunger valve 15 through the medium of the rod 18. In this way, whenever the carburetor valve is changed to regulate the amount of fuel passing from the carburetor 20 into the manifold, the plunger valve 15 will also be moved to vary the amounts of air passing into the manifold through the air ports 13 and 14.

To provide for the admission of steam or 25 moist air into the manifold in lieu of the dry air admitted therein through the ports 13 and 14, I have provided an arrangement consisting of a pipe 23 which has one end thereof threaded into or otherwise secured in one end of the bore 11. The opposite end of this pipe may be either extended through the top of an automobile radiator as shown or else inserted in the water jacket 30 of the engine by removing the safety plug ordinarily located on the right side of the engine block and directly to the right of the front cylinder and about one inch below the manifold, so as to receive therefrom moist air or steam, which is thus withdrawn 35 from the radiator or the water jacket through this pipe and into the intake manifold via the air ports 14. It will be understood, of course, that my invention is particularly adapted for use in connection with 40 motor vehicles and therefore it is thought that the connection of the pipe 23 with either the radiator or the water jacket will be readily understood. It will be noted that, 45 the pipe 23 is provided with a cut off valve

24 which is operated to close the passage 50 through the pipe when desiring to use merely the dry air admitted through the opening 13.

From the foregoing it is thought that the operation will be readily understood. In 55 this connection it is pointed out that whenever the arm 21 is actuated by the rod 22 to move the throttle valve to more open position, the rod 18 will move the plunger valve 15 in a direction to uncover one or more of 60 the openings 13 and 14 and in this way the proportion of air and gas admitted to the manifold inlet will be constant. It is desirable sometimes to use steam or moist air in preference to the dry air admitted through 65 the opening 13 and for this reason I have provided the pipe 23 which feeds a supply of moist air or steam from the radiator.

The foregoing description and the accompanying drawings have reference to what 70 might be considered to be the preferred or approved form of my invention. I desire it to be understood that I may make such changes in the combination, construction and arrangement of parts, materials, dimensions, et cetera as may prove expedient and fall within the scope of the appended claim.

Having thus fully described my invention, what I claim is:—

A device of the character described comprising a body portion provided with a central opening, and a longitudinally extending bore positioned above said opening, said bore communicating with said opening and provided with a plurality of air ports extending through the wall thereof, a feed pipe connected with one end of said bore to admit steam therein, a slide valve extended into the bore from the opposite end thereof to regulate the passage of steam and air into said central opening, an eye formed on the outer end of said valve, a rod extending through said eye and an actuating rod connected therewith.

In testimony whereof I affix my signature.

GEORGE A. PREISSER.
